TELEPHONE SUBSET

John Dominic Cuccio and Robert Andrew Chieda, Westport, Conn., assignors to International Telephone and Telegraph Corporation

Filed Apr. 9, 1965, Ser. No. 84,705

Term of patent 3½ years

(Cl. D26—14)

FIG. 1

FIG. 2

FIG. 3

FIG. 4

FIG. 5

FIG. 6

FIG. 7

FIG. 10

FIG. 8

FIG. 9

FIG. 1 is a front, top and right side perspective view of a telephone subset, showing one form of my new design having a dial wheel;

FIG. 2 is a top plan view of the form shown in FIG. 1;

FIG. 3 is a right side elevational view of the form shown in FIG. 1, the opposite side being substantially a mirror image thereof;

FIG. 4 is a front, top and right side perspective view of the form shown in FIG. 1 with the handset in resting position on the switch actuators;

FIG. 5 is a top and rear perspective view of the form shown in FIG. 1;

FIG. 6 is a left side, bottom and front perspective view of the form shown in FIG. 1;

FIG. 7 is a front, top and right side perspective view of a telephone subset, showing another form of my new design having push buttons;

FIG. 8 is a top and rear perspective view of the form shown in FIG. 7;

FIG. 9 is a right side elevational view of the form shown in FIG. 7, the opposite side being substantially a mirror image thereof; and

FIG. 10 is a top plan view of the form shown in FIG. 7. The handset has been omitted from FIGS. 1, 2, 3, 5, 6, 8, 9 and 10 for convenience in illustration. The characteristic features of our new design are shown in solid lines and reside in features such as the front end of the side view of the telephone coming almost to an arrow head like point. From the arrow head like point the

slope of the front top surface lessens slightly, nonetheless the top surface rises sharply to a point almost in line with the wells shaped to receive the handset. From this point the top surface of the subset descends at a relatively sharp slope to a point slightly past the end of the walls. There the slope becomes almost normal to the surface upon which the telephone is resting. The base of the telephone slopes sharply inward with the slope at the front end being sharper than the slope at the rear end. The well appears to be a truncated cone whose axis is normal to the surface upon which the subset is resting.

We claim:

The ornamental design for a telephone subset, as shown and described.
